UNITED STATES PATENT OFFICE.

HENRY D'OLIER, JR., OF RUTHERFORD, NEW JERSEY.

REFLECTOR ATTACHMENT.

959,205.

Specification of Letters Patent. Patented May 24, 1910.

Application filed October 7, 1908. Serial No. 458,656.

To all whom it may concern:

Be it known that I, HENRY D'OLIER, Jr., a citizen of the United States, residing at Rutherford, State of New Jersey, have invented certain new and useful Improvements in Reflector Attachments, of which the following is a specification.

My invention relates to reflector attachments, and particularly for use in connection with electric glow or incandescent lamps.

It is the object of my invention to provide an attachment for an electric lamp reflector which will serve to support the reflector from the lamp socket, at an angle or otherwise, so that the reflector may be easily and quickly adjustable to different angles with respect to the electric lamp or source of light; and it is the further object that such adjusting and fastening attachments be simple, cheap to manufacture, and easily attachable, and when attached, affording a firm and efficient support.

For an illustration of some of the forms my invention may take, reference is to be had to the accompanying drawing, in which:

Figure 1 is an elevational view of a lamp socket with a reflector supported thereby and adjustable with respect thereto, the reflector and the supporting and adjusting means being shown in vertical section. Fig. 2 is a perspective view of a resilient ring member. Fig. 3 is a plan view of a reinforcing or stiffening member. Fig. 4 is a fragmentary vertical section through an adjusting means taken at right angles to the section in Fig. 1. Fig. 5 is a vertical sectional view through a modified form of adjusting means.

Referring to the drawing, a lamp cord C, or other suitable, flexible or rigid support, disposed vertically or at any other angle, supports a lamp socket S, having a key K, here shown as one of the standard sockets used at present and having a bead b approximate its lower end. Into the lamp socket may be fitted an incandescent lamp L shown in dotted lines to indicate the position a lamp may take.

A resilient ring member R, shown separately in Fig. 2, is circumferentially discontinuous, a slot or gap g being provided to make such ring the more resilient. The ring R is provided with a bead c adapted to spring over and register with the lamp

socket bead b, and above this bead c the edge of the ring R is turned over as at d, to hold the resilient wire ring e which is also circumferentially discontinuous at f, 60 as seen in Fig. 3. This ring e is resilient and reinforces or stiffens the ring member R causing a more secure attachment between the ring R and the lamp socket. At some distance below the bead c a steep shoulder h 65 is provided to form between it and the lower lip or flange i a deep and substantially flat-sided groove to receive the turned-in edge of the shell j.

The shell or ball member j is preferably 70 spherical in shape and is partially surrounded by the similarly shaped shell or ball member k which has a bead l and a lip or flange m to receive the metal reflector or shade member n, having the inside reflecting 75 surface n'.

The shells or ball members j and k are secured together by eyelets o, as best seen in Fig. 4, such eyelets forming pivots upon which the shell k may move with respect to 80 the shell j.

Into the opening at the upper portion of the shell or ball member j is sprung the resilient ring member R, the same expanding 85 in such opening and engaging the edge of the member j in the groove formed between the steep sided bead h and the lip or flange i. The ring member R may then be sprung over the lamp socket, the bead c engaging the lamp socket bead b, the resilient reinforcing ring e serving to stiffen and 90 strengthen the support.

As it is often desirable to direct the reflected light from an incandescent lamp in different directions, the reflector n may be 95 tipped or tilted one way or the other about the pivotal axis as determined by the eyelets o, the opening in the shell member k being sufficiently great to form a wide mouth to allow a substantial angle of movement about the pivots before contacting with the globe or shell of the lamp L. Furthermore, with any angular position of the reflector n with regard to the axis determined by the pivots, the reflector n may also be 100 rotated around the lamp or socket axis either where the shade n engages between the steep sided bead l and the lip m or by the rotary movement of the shell or ball j upon the ring member R. Thus, it is seen 105 that the reflector may be tilted with respect to the lamp or socket axis and may also be

rotated around the lamp or socket axis. The adjustment of the shade *n* serves also for changing the relative positions of the reflector surface and the source of light to afford different degrees of dispersion or concentration of the reflected rays. Here the reflector *n*, as shown, is a surface of revolution, as the preferred form, and has its axis at an angle to the attachment axis which, in this case, means also at an angle to the lamp or socket axis.

In Fig. 5 is shown a modification of the mode of engagement between the shell or ball members *j* and *k*. These members are here represented as being spherical in form, one of the horizontal axes of the sphere being indicated at X—X. The shell *k* extends a considerable distance above the axis X—X and the member *j* extends a considerable distance below that axis, so that these members overlap for a considerable zone of a sphere, this overlapping beyond the axis preventing their falling or coming apart. A shade held by the member *k* may be adjusted through an angle with respect to the member *j*, but this adjustment is not confined about any particular axis as in Fig. 4, but may be about any axis. In other words, the adjustment means of Fig. 5 is more universal than that shown in Figs. 1 and 4.

The ring member *R* and the members *j* and *k* and the reflector or shade member *n* may preferably be formed out of sheet brass, or other sheet metal by spinning or by any other suitable process.

From the foregoing description it follows that a reflector or shade member may be disposed with its axis at an angle with the axis of an incandescent lamp, be adjustable with respect to the lamp about one or more axes, and may also rotate around the axis of the lamp or socket; and that I have provided a simple, cheap, and effective attachment, for securing either directly or indirectly a shade or reflector to a lamp socket, and that I have provided angular adjusting means, either about a single or plurality of axes, in the form of wide mouthed ball or spherical members.

What I claim is:

1. In combination, a lamp socket, a bead thereon, a reflector or shade, means for supporting said reflector or shade upon said lamp socket comprising a resilient ring member having a bead adapted to register with said lamp socket bead, a reinforcing ring on one side of said bead on said ring member, and a steep shouldered bead and a flange upon said ring member.

2. A reflector or shade attachment comprising a resilient ring member, a bead thereon, a reinforcing ring secured by said ring member on one side of said bead, a second bead, a lip or flange, and a groove formed

between said second bead and said lip or flange.

3. The combination with a lamp socket, of a lamp held thereby, a resilient ring member attached to said socket, a member circumferentially surrounding said lamp and supported by said ring member, a reflector or shade, a member to which said reflector or shade is attached and extending around said lamp, and a pivotal connection between said members, whereby said reflector or shade may be tilted with respect to said lamp socket.

4. The combination with a lamp socket, of a ball member attached thereto, a second ball member, said ball members being attached to and movable with respect to each other, and a shade or reflector supported upon said second ball member.

5. In combination, a reflector or shade member having an aperture therein, a ball member adapted to engage said reflector or shade member and having a mouth coaxial with said aperture, and a second ball member attached to and movable with respect to said ball member.

6. The combination with a reflector or shade, of a ball member attached thereto, a second ball member attached to and movable with respect to said ball member and having an aperture therein, and a resilient ring member engaging said second ball member in said aperture.

7. The combination with a lamp socket, of a reflector or shade, and means for adjustably supporting said reflector or shade with respect to said lamp socket comprising wide mouthed ball members adapted to surround the lamp and attached to and movable with respect to each other; one of said ball members attached to said socket, and said reflector or shade attached to another of said ball members.

8. The combination with a lamp socket, of a shade or reflector member, means for supporting said shade or reflector with its axis at an angle with the axis of said lamp socket and for rotation of said reflector or shade about the axis of said lamp socket, and means for adjusting said shade or reflector to different angles with respect to said lamp socket.

9. The combination with a lamp socket adapted to receive a lamp, of a shade or reflector member, means for supporting said shade or reflector upon said socket independently of said lamp and with its axis at an angle with the axis of said lamp socket, and means for adjusting said shade or reflector to different angles with respect to said lamp socket.

10. The combination with a lamp socket, of a lamp held thereby, a member circumferentially surrounding said lamp and supported by said socket, a reflector or shade, a second member to which said reflector or shade

is attached and extending around said lamp, and a pivotal connection between said members, whereby said reflector or shade may be tilted with respect to said lamp socket.

11. The combination with a lamp socket, of a lamp held thereby, a member extending beyond said socket and circumferentially surrounding said lamp and supported by said socket, a reflector or shade, and a pivotal connection between said reflector or

shade and said member, whereby said reflector or shade can be tilted with respect to said lamp socket.

In testimony whereof I have hereunto affixed my signature in the presence of the two 15 subscribing witnesses.
